DESIGN FOR AN EMBLEM BADGE

Alfred H. Lantau, Philadelphia, Pa.

Application March 2, 1945, Serial No. 118,231

Term of patent 14 years

(Cl. D29—2)

To all whom it may concern:

Be it known that I, Alfred H. Lantau, a citizen of the United States, residing at Philadelphia, in the county of Philadelphia and State of Pennsylvania, have invented a new, original, and ornamental Design for an Emblem Badge, of which the following is a specification, reference being had to the accompanying drawing, forming part thereof, in which the figure is a perspective view of an emblem badge illustrating my new design.

I claim:

The ornamental design for an emblem badge, as shown.

ALFRED H. LANTAU.
